CLAIM

The ornamental design for a chair, as shown and described.

DESCRIPTION

FIG. 1 is a front perspective view of a chair.

FIG. 2 is a front view of the chair of FIG. 1.

FIG. 3 is a rear view of the chair of FIG. 1.

FIG. 4 is a left-side view of the chair of FIG. 1.

FIG. 5 is a right-side view of the chair of FIG. 1.

FIG. 6 is a top view of the chair of FIG. 1; and,

FIG. 7 is a bottom view of the chair of FIG. 1.

In the drawings, the ornamental design that is claimed is shown in solid lines. The broken lines form no part of the claimed design.
